Primary Examiner — Paula Allen Greene

(74) Attorney, Agent, or Firm — David W. Carstens;
Carstens, Allen & Gourley, LLP(57) **CLAIM**

The ornamental design for a tulip shaped urn, as shown and described.

DESCRIPTION

FIG. 1 is a front perspective view of a tulip shaped urn of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an exploded perspective view thereof.

The broken lines in FIG. 6 depict a portion of the tulip shaped urn that forms no part of the claimed design.
